UNITED STATES PATENT OFFICE.

NEWMAN H. HOLLAND, OF WEST ORANGE, NEW JERSEY, ASSIGNOR TO NEW JERSEY PATENT COMPANY, OF WEST ORANGE, NEW JERSEY, A CORPORATION OF NEW JERSEY.

PHONOGRAPH.

1,275,257.

Specification of Letters Patent. Patented Aug. 13, 1918.

Application filed February 16, 1914. Serial No. 818,892.

To all whom it may concern:

Be it known that I, NEWMAN H. HOLLAND, a subject of the King of Great Britain, and a resident of West Orange, Essex county, 5 New Jersey, have made certain new and useful Improvements in Phonographs, of which the following is a description.

My invention relates to phonographs and more particularly to phonographs of the 10 business or commercial type. It has for its primary object to provide improved means whereby the reproducer stylus of the phonograph can be moved or spaced back for the purpose of causing the repetition of any 15 portion of the record whenever the operator who is transcribing the record so desires. I preferably attain this object by means of a construction wherein the reproducing stylus can be shifted back over 20 a part of the record to repeat the same without the necessity of being lifted from the record, this construction greatly facilitating the rapidity and efficiency of operation of the back spacing device.

25 A further object of my invention is to provide an improved construction wherein the controlling means for the back spacing mechanism may be positioned at a convenient position for actuation by the transcriber while the latter is operating the typewriting machine, the preferred position for this purpose being adjacent the keyboard of said machine. My invention also 30 comprises certain details of construction 35 which will be hereinafter more fully set forth.

The drawings illustrate one embodiment of my invention, the same characters being used to designate the same parts in all the 40 views. On said drawings—

Figure 1 is a rear elevation partly in section of said embodiment of my invention;

Fig. 2 is a transverse vertical section taken on the line 2—2 of Fig. 1;

45 Fig. 3 is a view partly in vertical section and partly in elevation of a detail of construction;

Fig. 4 is a vertical sectional view taken on the line 4—4 of Fig. 2;

50 Fig. 5 is a view similar to Fig. 4 showing the same parts in a slightly different position;

Fig. 6 is a view partly in horizontal section and partly in plan of a detail of construction; and

Fig. 7 is a perspective view of one of the elements of the back spacing means.

In the drawing, the numeral 1 designates a phonograph record or blank which is rotatably mounted upon a frame or support 2. 60 In proximity to this record is an arm or traveling carriage 3 which supports a pivoted frame 3' in which the recorder and reproducer are mounted. The reproducer and recorder may be of any suitable construction, the numeral 4 designating the reproducer stylus which is adapted to track the grooves in the record 1. A suitable form of reproducer is disclosed in my application Serial No. 776,463 filed June 30, 1913, 70 and entitled Phonograph reproducers. The numeral 4' designates the stylus of the recorder, which may, if desired, be entirely omitted. A feed screw 5 is mounted in bearings formed in standards 6 which project upwardly from the top of the table 2. A pulley 7, over which runs a driving belt 8, operated by any suitable means, imparts rotation to the mandrel 9 through the mandrel shaft (not shown). The mandrel carries the record or blank 1. The feed screw 5 carries a gear 10 which meshes with a similar gear (not shown) on the mandrel shaft whereby rotation may be imparted to the feed screw in a manner well known in the phonograph art. The feed screw coacts with a feed nut 11 connected to the arm 3 to move the latter and the parts carried thereby along the record or blank 1.

The arm 3 and the structure supported 90 thereby is mounted to slide along a rotatable back rod or rock shaft 13 and for this purpose the arm is provided with a hub 14 having an extension 15, the hub 14 and extension 15 being both slidable and rotatable 95 on said rod. The forward end of arm 3 slides upon a guide rod 15' running from one side of the machine to the other. The hub 14 is provided with an enlarged opening or recess 16 for receiving certain elements hereinafter referred to. As shown in Fig. 1, the extension 15 is of less outside diameter than the hub 14, a shoulder being thus formed at the inner end of the extension 15. Through a screw threaded opening in this shoulder passes a small screw 17, the inner end of which projects into the opening or recess 16 and engages an annular cam disk 18, which is mounted to move along the spindle 13 with the arm 3. 110

The inside diameter of this disk is slightly larger than the diameter of the spindle 13, and into the central opening through the disk projects a radially disposed pin 19 which engages a keyway 20 extending along the spindle 13 substantially from one end to the other thereof. This pin causes the cam disk 18 to rotate with the spindle 13 whenever the same is 10 rocked, no matter at what point along the spindle 13 the cam disk may be, while at the same time leaving the cam disk free to slide along the spindle as much as necessary. On the face of disk 18 which is turned 15 toward the screw 17, this disk is provided with a recess 21, one edge of which is abrupt or at right angles to the face of the disk and the other of which is inclined to said face, as shown at 22 in Figs. 6 and 7. This 20 recess receives the projecting end of the screw 17, and the parts are arranged in such a way as to cause the disk to abut against the side of the recess through which the screw 17 projects and the inner end of this 25 screw to rest against the abrupt side of the notch 21 when the disk has its pin engaging the keyway 20 and the arm 3 is moving along the record or blank 1.

With the above construction in view it 30 will now be clear that if the back rod or shaft 13 is rocked in the direction shown by the arrows on Figs. 4 and 6, the arm 3 and the hub 14 and extension 15 being loose on the shaft and not engaging the keyway 20 35 will not be rocked with the shaft 13, but the cam disk 18 will be moved so as to carry the inclined edge 22 of the recess over the inner end of the screw 17. Owing to the 40 fact that the opening through the cam disk is slightly larger than the diameter of the rod 13, the first effect of this movement is to tilt or cant the disk from the position shown in Fig. 4 to the position shown in Fig. 5 in which latter position the cam disk 45 binds or "bites" upon the rod 13, and cannot be tilted on the rod or pushed along the same any farther. If, however, the rod 13 rotates a little more, the inclined edge 22 of the recess 21 now has a cam action on the 50 screw 17 and produces bodily movement of the arm 3 through the hub 14 and the extension 15. This bodily movement carries the arm 3 to the right, as shown by the arrow in Fig. 1, and as the arm 3 is not 55 lifted in the rocking of the rod 13, the stylus 4 is not lifted, but slides or skids along the record 1 until it again comes to rest in one of the sound wave grooves at a point which it has already passed. In the operation of 60 my invention, when the spindle 13 is released and moved back to its original position, the cam washer moves back with it and the parts resume the relative positions shown in Figs. 4 and 6. In this way, the stylus is 65 spaced back to a position from which it is ready to repeat a part of the record. A compression spring 23, encircling the rod 13 in the recess 16, engages at one end with the cam disk 18 and holds it in position to act upon the screw 17 at all times, in the manner above set forth.

When the arm 3 is to be shifted back, it is necessary to disengage the feed nut 11 from the feed screw 5. For this purpose, my invention comprises a part 24 projecting 70 from hub 14 and having downturned lugs 25 between which is pivotally mounted a lever 26. This lever 26 carries a spring arm 27 which extends toward the screw 5, and carries at its outer end the feed nut 11, 80 which engages the upper portion of the feed screw 5. So long as the threaded shaft 5 turns clock-wise, viewing the same from the right on Fig. 1, the arm 3, with the parts carried thereby, will be moved along the 85 spindle 13 to the left, because of the engagement of the feed nut with the feed screw. When the feed nut 11 is lifted from the feed screw, the arm 3 is free to move backward. A spring 29 secured at its upper end to the 90 arm 3 presses downward upon the arm 27 and holds the feed nut against the feed screw, an adjusting screw 30 passing through the lever 26 from below and engaging the lower side of the spring-arm 27 to adjust the 95 position of the feed nut with respect to lever 26 and feed screw 5. The feed nut 11 is adapted to be lifted from the feed screw 5 by means of a disk-like cam 31 located in recess 16 and mounted on rod 13, cam 31 100 having a pin 31' similar to the pin 19 of the washer 18 to engage the keyway 20. This cam is engaged by the spring 23 and is forced by it against the side of the recess 16 opposite that occupied by disk 18. One side 105 of the lever 26 overlaps the edge of this recess as shown in Figs. 1 and 4, and this portion of the lever 26 is moved by the cam when the spindle 13 and cam 31 are rocked through a certain angle, to press the rear end of the 110 lever 26 downwardly against the force of the spring 29 to lift the feed nut 11 from the feed screw 5. The cam 31 slides with the arm 3 along the rod 13 and can be turned by this rod when the arm 3 is in any position longitudinally of the said rod, the same 115 as the cam washer 18.

In order to permit rocking or rotation of the rod 13 through a sufficient angle to operate the cam 31, to free the arm from the 12 feed screw 5, and to operate the disk 18 to shift the arm 3 backward, I mount the rod 13 in bearing blocks 32, secured in the upper ends of the standards 6 and provided with bores which receive journals or trunnions 33 13 at the ends of the rod 13. I also secure to one end of the shaft an operating arm 34 which is fixed thereon so that when the arm is actuated, the shaft 13 must rock. This arm is engaged by a spring 35, which is 1

made fast thereto at one end, and, after encircling the shaft 13, is fixed at the other end to the top of the adjacent standard 6. Normally this spring holds the arm in such position that it extends vertically downward, so as to keep the keyway 20 on the under side of the shaft and the feed nut 11 in engagement with the feed screw. In order to provide means for moving the arm 34 and rocking rod 13, I connect the said arm to the armature of an electromagnet, which is in circuit with a suitable source of electricity, the circuit being adapted to be closed to energize the magnet whenever the operator desires. This armature is provided at its upper end with a member 36 said member having an elongated slot 36' containing a pin 34' on arm 34. The armature is shown at 37 supported to extend upward from a suitable pivot 37' in a frame 38 on the table 2. This frame also carries the core 39 and coil 40 in position to attract the armature 37; and also secured to this frame is an upwardly extending spring arm 41, having a cushion 42 on its upper end to act as a buffer for the member 36 and prevent the spring 35 from moving the arm 34 beyond vertical position when the armature is not attracted by the magnet. The magnet is supplied with current from the suitable source of electricity, such as a battery 43, and the circuit is arranged to be opened and closed by means of a switch 44. The preferred construction for this switch is disclosed and claimed in my copending application, Serial No. 818,894 filed Feb. 16, 1914, on which Patent No. 1,214,920 was granted to me on February 6, 1917.

The following is a description of the operation of my invention. The driving mechanism for the phonograph being set into operation, the stylus 4 will run along through the grooves in the record 1 in the manner required to accurately reproduce the record. If, however, the operator should fail to understand fully any part of the record and for this or any other reason should desire to have a part of the record repeated, it is only necessary to close the switch 44 to produce this result. The closing of the switch energizes the coil 40 which thereupon attracts the armature 37 and causes the same to swing the arm 34 to the right, viewing the apparatus as shown in Fig. 2, the arm 34 rotating the shaft 13 through a certain angle. Through the keyway 20 in the shaft 13, the cam 31 is rotated to press down the rear end of lever 26 and raise the feed nut 11 from the feed screw 5. At the same time, the shaft 60 rotates the cam disk 18, with the result that the cam disk is first tilted because of the action of the cam surface 22 on the inner end of the screw 17 into binding engagement with rod 13, as shown in Fig. 5, the further rotation of the shaft causing the cam sur-

face 22 to exert a thrust on the screw 17 to shift the arm 3, with the parts carried thereby, in a backward direction, shown as above mentioned, by the arrow on Fig. 1. The parts are so designed that the binding 70 of the disk 18 on the rod 13 takes place before the rocking of the rod 13 by the arm 34 is finished. Since the arm 3 is not raised when shifted back, the stylus 4 is caused to slip or skid quickly along the surface of the record across the record grooves during the back spacing operation, but as the stylus is rounded and moves across the grooves very rapidly, it does not substantially scratch or otherwise mar the record. This very rapid movement of the stylus across the record grooves is due to the fact that the means comprising the members 34, 13, 18 and 17 for shifting the arm 3 and parts carried thereby along the record is directly actuated or energized by the electrical means comprising the magnet 40 and its armature 37, as distinguished from being controlled in its action by such electrical means. The switch 44 is then reopened whereupon the magnet 80 releases the armature 37 and the spring 35 rocks the arm 34 back to vertical position causing the member 36 to abut against the cushion 42 on the spring arm 41. The rotation of the arm 34 causes the rod 13 to return to its normal position, the feed nut 11 being thus moved back into engagement with the feed screw 5 and the cam disk 18 assuming the position shown in Figs. 1 and 6. The apparatus is now ready to repeat a part of the record. The whole operation of shifting back is instantaneously effected by pressing upon the switch 44, which may be automatically opened, as by a spring 45, when the pressure thereon is removed. The stylus is spaced back a given amount each time the switch is closed. If the stylus is not spaced back far enough upon one closure of the switch, the necessary amount of back spacing can be obtained by closing the switch 100 a number of times.

From the above description it will be seen that my invention is simple and that it will operate with quickness, ease and certainty to produce the required effect, at any point in the reproduction of the record, the cam disk 18 and the cam 31 moving along with the arm 3 and being capable of being operated instantaneously, regardless of the point where they may be on the shaft 13. Furthermore the parts are comparatively few in number and there is little likelihood of the apparatus getting out of order. My invention is, therefore, of great commercial value and capable of satisfactory and long continued operation under the requirements and conditions of every day use. The fact that the arm 3 is not raised when any part of the record is repeated, whereby the stylus 4 is not lifted from the record, but skids rapidly 110 115 120 125 130

over the surface thereof is an important feature of my invention, the efficiency and simplicity of the apparatus being thereby increased.

5 I wish to have it understood that the above description and the accompanying drawings disclose but one embodiment of my invention; and are, therefore, to be construed as being illustrative only. Many changes may 10 be made in the construction disclosed without departing from the spirit of my invention.

Having described my invention what I claim as new and desire to protect by Letters Patent of the United States is as follows:

1. In a phonograph, the combination of a support for a record, sound reproducing means comprising a stylus adapted to track 20 the record, electrical means, and means directly actuated by said electrical means to shift said stylus back toward the beginning of the record while permitting the same to remain in contact with the record, substantially as described.

2. In a phonograph, the combination of a support for a record, a sound reproducing device comprising a stylus adapted to track the record, means for moving said device 30 relatively to the record to feed the stylus along the record, electrical means and means directly actuated by said electrical means to render said moving means inoperative and to simultaneously shift the stylus back toward the beginning of the record while permitting the same to remain in contact with the record, substantially as described.

3. In a phonograph, the combination of a support for a record, a rock shaft, sound reproducing means slidably mounted on said shaft and comprising a stylus adapted to engage the record, feeding means for moving said sound reproducing means in a given direction along said shaft, and means for 40 rendering said feeding means inoperative and for shifting said sound reproducing means along said shaft in the opposite direction while permitting said stylus to remain in engagement with the record when said shaft is rocked in a given direction, substantially as described.

4. In a phonograph, the combination of a support for a record, a rock shaft, sound reproducing means slidably mounted on said shaft and comprising a reproducer stylus, and means for moving said sound reproducing means along said shaft when the latter is rocked in a given direction, said sound reproducing means and stylus being mounted to permit the stylus to remain in engagement with the record during the rocking of said shaft in said direction, substantially as described.

5. In a phonograph, the combination of a support for a record, a rock shaft, sound re-

producing means movably mounted on said shaft and comprising a reproduced stylus, feeding means for moving said sound reproducing means along the shaft and means for rendering said feeding means inoperative when said shaft is rocked in a given direction, said sound reproducing means and stylus being mounted to permit the stylus to remain in engagement with the record during the rocking of said shaft in said direction, substantially as described. 75

6. In a phonograph, the combination of a rock shaft, sound reproducing means slidably mounted on said shaft, and means comprising a disk carried by said shaft and 80 movable along the same with said sound reproducing means for moving said sound reproducing means along said shaft when the latter is rocked in a given direction, substantially as described. 85

7. In a phonograph, the combination of a shaft, sound reproducing means supported thereby, and mechanism for moving said sound reproducing means along said shaft, said mechanism comprising a member carried by said shaft and adapted to be tilted into binding engagement therewith, substantially as described. 90

8. In a phonograph, the combination of a shaft, sound reproducing means supported 95 thereby, and mechanism for moving said sound reproducing means along said shaft, said mechanism comprising a cam carried by said shaft and adapted to be tilted into binding engagement therewith, substantially as described. 100

9. In a phonograph, the combination of a shaft, sound reproducing means supported thereby, and mechanism for moving said sound reproducing means along said shaft, 105 said mechanism comprising a cam disk encircling said shaft, carried by said shaft, and adapted to be tilted into binding engagement therewith, substantially as described. 110

10. In a phonograph, the combination of a shaft, sound reproducing means supported thereby, and mechanism for moving said sound reproducing means along said shaft, said mechanism comprising a member carried by said shaft and adapted to be tilted into binding engagement therewith, and resilient means opposing the tilting of said member, substantially as described. 115

11. In a phonograph, the combination of a support for a record, a rock shaft having a longitudinal keyway therein, a device for reproducing a record slidably mounted on said shaft and comprising a reproducer stylus, and means mounted on said shaft, engaging 120 the keyway therein, movable along the same with the reproducing device, and operable by the rocking of the shaft to shift said device along the shaft, said device and stylus being mounted to permit the stylus to re- 125 130

main in engagement with the record during the rocking of said shaft, substantially as described.

12. In a phonograph, the combination of 5 an electro magnet having an armature, a record support, means for reproducing a record mounted on said support, means for energizing the magnet, and means directly actuated by the armature to shift the reproducing means back toward the beginning of the record while permitting said sound reproducing means to remain in engagement with the record, substantially as described.

13. In a phonograph, the combination of a 15 record support, means for reproducing a record carried by said support, a rock shaft having an arm, a magnet having a pivoted armature engaging said arm, means for actuating the magnet, and means operated by 20 the rock shaft for causing the reproducing device to be shifted back toward the beginning of the record when the magnet is actuated, substantially as described.

14. In a phonograph, the combination of a 25 record support, means for reproducing a record carried by said support, an arm carrying said means, a rod on which said arm is slidably mounted, a cam disk movable with said arm and slidably mounted on said rod, 30 said disk having a cam-shaped recess in one face, and means projecting into said recess, and coacting with the surface thereof to tilt the disk into binding engagement with said rod when said arm and rod are moved relatively to each other, substantially as described.

15. In a phonograph, the combination of a support for a record, a device for reproducing the record, a shaft having a rock arm 40 thereon, a magnet provided with a pivoted armature having a pin and slot connection with said arm, electrical means for energizing the magnet, and means actuated when the arm is rocked to cause said device to be 45 shifted back toward the beginning of the record, substantially as described.

16. In a phonograph, the combination of a support for a record, a device for reproducing the record, a shaft having a rock arm 50 thereon, resilient means tending to hold said arm in a given position, a magnet provided with a pivoted armature having a pin and slot connection with said arm, electrical means for energizing the magnet, and means 55 actuated when the arm is rocked to cause said device to be shifted back toward the beginning of the record, substantially as described.

17. In a phonograph, the combination of a 60 electro-magnet having an armature, a support for a record, means for reproducing a record mounted on said support, means for

energizing the magnet, and means directly actuatable by the armature and operable by repeated energizing of the magnet to shift 65 the reproducing means successively predetermined distances back toward the beginning of the record while permitting said reproducing means to remain in engagement with the record, substantially as described. 70

18. In a phonograph, the combination of a support for a record, a rock shaft, sound reproducing means carried by and movable along said shaft and comprising a stylus, an electro-magnet having means for rocking 75 said shaft, and means operated by the rocking movement of said shaft for moving said sound reproducing means along said shaft a predetermined distance, said sound reproducing means and stylus being mounted to 80 permit the stylus to remain in engagement with the record during the rocking of said shaft, substantially as described.

19. In a phonograph, the combination of a record support, means for reproducing a 85 record carried by said support, an arm carrying said means, a rod on which said arm is slidably mounted, a disk having a cam surface movable with said arm and slidably mounted on said rod, and means engaging said cam surface to tilt the disk into binding engagement with said 90 when said arm and rod are moved relatively to each other, substantially as described.

20. In a phonograph, the combination of a 95 support for a record, a device for reproducing the record, a shaft having a rock arm thereon, resilient means tending to hold said arm in a given position, a magnet provided with a pivoted armature coacting with said 100 arm, electrical means for energizing the magnet, and means actuated when the arm is rocked to cause said device to be shifted back toward the beginning of the record, substantially as described.

21. In a phonograph, the combination of a support for a record, sound reproducing means comprising a stylus adapted to track a record, a source of energy, means directly actuated through the medium of said source 110 of energy and predetermined to give to said stylus a rapid momentary movement back toward the beginning of the record while permitting the stylus to remain in contact with the record, and means for controlling 115 the operation of said last mentioned means and said source of energy, substantially as described.

This specification signed and witnessed this 13th day of February 1914.

NEWMAN H. HOLLAND.

Witnesses:

FREDERICK BACHMANN,
MARY J. LAIDLAW.

It is hereby certified that in Letters Patent No. 1,275,257, granted August 13, 1918, upon the application of Newman H. Holland, of West Orange, New Jersey, for an improvement in "Phonographs," an error appears in the printed specification requiring correction as follows: Page 4, line 67, claim 5, for the word "reproduced" read *reproducer*; page 5, line 64, claim 17, for the word "actuable" read *actuable*; and that the said Letters Patent should be read with these corrections therein that the same may conform to the record of the case in the Patent Office.

Signed and sealed this 24th day of December, A. D., 1918.

[SEAL.]

F. W. H. CLAY,

Acting Commissioner of Patents.
